UNITED STATES PATENT OFFICE.

WILLIAM H. GAULKE, OF MILWAUKEE, WISCONSIN, ASSIGNOR TO INDEPENDENT ELECTRIC MFG. COMPANY, OF MILWAUKEE, WISCONSIN.

CIRCUIT-CHANGING DEVICE.

1,069,610.

Specification of Letters Patent.

Patented Aug. 5, 1913.

Application filed September 26, 1911. Serial No. 651,459.

To all whom it may concern:

Be it known that I, WILLIAM H. GAULKE, a citizen of the United States, residing at Milwaukee, in the county of Milwaukee and 5 State of Wisconsin, have invented a certain new and useful Improvement in Circuit-Changing Devices, of which the following is a full, clear, concise, and exact description, reference being had to the accompanying drawings, forming a part of this specification.

My invention relates to circuit changing devices, and in the embodiment shown herein is more particularly of service in connection with a multiple switch, one of whose many uses as illustrated herein consists in its application to starting devices for machinery.

More particularly my invention contemplates a device in which a plurality of contacts may be successively made, and may if desired be successively opened in reverse order to the making.

The device also contemplates means whereby one or the other of the aforesaid operations, that is the making or the breaking of all of the contacts may be simultaneously done.

My invention in one of its embodiments is of great utility in connection with heavy duty electrical power service when large motors, for instance, may be started, which motors are started as is well understood by effecting a series of successive circuit changes until the motor is finally in operation. My invention sets forth means for making these successive circuit changes, preferably by hand, each circuit change being controlled by a substantial circuit controlling element or elements of the character to control circuits of considerable amperage and widely different therefore from the ordinary starting rheostats with their slidable handle successively slidably engaging a plurality of contacts arranged in its path of operation. My invention also contemplates the provision of means whereby these same contact making elements may be successively operated, preferably in reverse order to open the circuits controlled thereby, suitable means, electromagnetic, if desired, being also provided whereby the entire circuit controlling elements may be jointly operated, for instance, if unusual

electrical conditions affect the devices or circuits under the control of my improved device.

I will explain my invention more in detail with reference to the accompanying drawings illustrating one embodiment thereof, in which:

Figure 1 is a side view of a device constructed in accordance with my invention; Fig. 2 is a top view thereof; and Fig. 3 is a detail view of a cam.

Referring to the figures, I set forth a plurality of contact brushes 1 suitably mounted and secured to angle pieces 2, 2, which in the form herein shown form one terminal of a circuit to be controlled. There are as many circuits as there are brushes of this character and the co-operating contact of each circuit consists of a switch element 3 suitably mounted upon an arm 4, all of the arms 4 being independently but rotatably mounted on the shaft 5 and suitably insulated from one another in any desired manner so as to preserve the individuality of the switch element 3 as may be desired. Supplemental carbon breaks are provided for each pair of contact terminals 1 and 3 and these carbon breaks consist of the carbon blocks 6 and 7, of which the block 6 is mounted on a spring angle piece 8 suitably secured to an angle piece 2, and the block 7 is secured by a suitable spring angle piece 9 to the arm 4. The shaft 5 is mounted in suitable bearings at its opposite extremities which are secured to the base plate 11. The base plate 11 is suitably mounted on an insulating plate 12, which insulating plate also carries the angle pieces 2. Each arm 4 has a bracket 13 carrying a roller 14 by means of which through the use of suitable cams 15, 16, 17, 18 and 19 said arms may be independently controlled as will be set forth directly. When the cams 15 to 19 inclusive are not in engagement with any of the rollers 14 the switch arms 4 are in the position shown by the left hand arm of Fig. 1. Whenever a roller 14, however, is engaged by its corresponding cam, then the corresponding arm 4 occupies the circuit closing position of the right hand arm 4 of Fig. 1.

By virtue of the construction which will now be described, it will be seen that the arms 4 may be successively brought into contact making position beginning from the

right hand end (Fig. 2) and may thereafter be successively released from this contact making position beginning preferably at the left hand end (Fig. 2). The cams 15, 16, 17, 18 and 19 are substantially similar in shape and their structure will be understood by referring to Fig. 3, in which cam 15 is set forth which has an outer circular surface 20 and a circular surface 21 of less diameter which are joined by the surface 22 to form an edge 23. These cams are all mounted on a shaft 24, which shaft also carries fixedly secured thereto two ratchet wheels 25 and 26, 26 being a right hand ratchet wheel and 25 a left hand ratchet wheel. The cams, however, although fixedly secured to the shaft are so arranged that the edge 23 in each of the cams occupies a different angular position with respect to its adjoining cam, as will be apparent from an inspection of Fig. 2. When the rollers rest against the surfaces 21 the arms 4 are in their open circuit position and when the rollers rest against the surfaces 20, the arms 4 are in their contact making positions. As in the course of the clockwise revolution of the shaft 24, the surfaces 20 of the respective cams are one after another brought into association with the rollers 14 so the arms 4 are successively placed in their contact making position during the continued clockwise operation of the said shaft 24. A reverse operation of said shaft will successively release the arms 4 in the reverse order as will be apparent. The shaft 24 carries a loosely mounted handle 27, rotatable thereon. The shaft 24 is held in a suitable bearing 28 mounted on a standard 29 of the plate 11. A pin 30 is mounted on this standard 40 and two arms 31 and 32 of the handle 27 limit the angular movement of said handle about said shaft. The handle 27 carries a pawl 33 controlled by a spring 34 which is adapted to engage the teeth of the step-by-step wheel 26. The handle 27 also carries a pawl 35 which is adapted under certain conditions to engage the step-by-step wheel 25. Thus if the handle 27 is moved in a clockwise direction the pawl 33 engages the teeth of the wheel 25 and moves the shaft 24 a specified angular distance forward, controlled by the arms 31 and 32, which angular forward movement of the shaft is sufficient to bring the first cam 15 into engagement with the roller 14 corresponding thereto, to place the first arm 4 into contact making position. The handle thereupon rotates to the position shown in Fig. 1 and a further angular forward movement brings the cam 16 into operative position to bring the second arm 5 into its contact making condition. Similarly the remaining arms are successively acted upon. Now should it be desired to release these arms successively for speed control purposes for instance, then

a supplemental plunger 36 is pushed down, which thereby leaves the pawl 33 in a position where it cannot engage the teeth of the wheel 26 and places the pawl 35 in such a position that it engages the teeth of the wheel 25. Then if the handle is operated forward and back, it will successively operate upon the arms 4 beginning at the left hand end of Fig. 2. In this way the arms 4 may be independently controlled and successively actuated. It sometimes is advisable to break all of the contacts practically simultaneously and this is accomplished by means of a notched bar 37 slidable within a bearing 38 and pivotally secured to a link 39, which link 39 is pivotally secured to the wheel 26 by means of the screw 40. Thus this arm 37 being movable with the wheel 26 corresponds in position to the angular position of the shaft 24 and a plurality of notches 41 are provided so that a notch 41 is in association with the catch 42 for each resting position of the shaft 24. Electromagnetic means 43 control the association of the catch 42 with the slide 37 and when unusual circuit conditions obtain, a deenergization of the means 43 releases the catch 42 from engagement with the slide 37, thereby permitting a spring 44 to rotate the shaft 24 in a contra-clockwise direction permitting a practically simultaneous release of all the arms 4 from their contact making position. This is due to the fact that the pawl 35 never engages the wheel 25 except when the plunger 36 is depressed, and due to the fact that the pawl 33 does not engage the teeth of the wheel 26 when the handle 27 is in the position of Fig. 1. This is accomplished by the following instrumentalities. These instrumentalities include an arm 45 mounted to the base 12 by means of its angular extension 46 on which are mounted two cam surfaces 47 and 48. When the arm 33 is moved in a contra-clockwise direction (Fig. 1), as when the handle is being restored to its normal position, this arm or pawl 33 rides over a tooth of the wheel 26 and before leaving this tooth engages the cam surface 48 by which it is further released from engagement with said tooth. When the arm 27 finally reaches its limiting position, the pin 49 on this pawl has left the cam 48 and slid into engagement with the cam 47. A further forward movement of the arm 27 will then immediately release the pawl 33 and permit it to engage the next succeeding tooth or rather the one over which it has just passed in its reverse motion. The catch 42 is of such a character that although the catch normally holds the bar 37 in a given position where it engages one of the notches thereof, yet by exerting sufficient force against the handle 27 the slide 37 may be moved without injury to the parts.

It will of course be understood that I have herein specifically described one form which my invention may take. It is susceptible of a variety of modifications and different uses to which in accordance with the terms of the claims I am entitled.

Having however, thus described a specific form of carrying out my invention, what I claim as new and desire to secure by Letters Patent is:

1. A device of the character described comprising a plurality of independent circuit controlling elements, means uncontrolled by said elements for successively operating said elements to place all of them in a given circuit changing position, means for successively actuating said elements to restore them to normal condition, a locking device for said means to retain them in their limiting or intermediate positions, and electro-magnetic means to control the simultaneous restoration of said elements to normal.

2. A device of the character described having a plurality of circuit changing elements, and a plurality of cams adapted to successively actuate said elements, said cams being mounted on a shaft, a step-by-step element associated with said shaft to periodically rotate said shaft, and electromagnetic means to control the simultaneous restoration to normal of said circuit changing elements.

3. A device of the character described having a plurality of circuit changing elements, a plurality of cams adapted to successively actuate said elements, said cams being mounted on a shaft, a step-by-step element associated with said shaft to periodically rotate said shaft in a given direction, a second step-by-step element to periodically actuate said shaft in the reverse direction, and electromagnetic means to control the simultaneous restoration to normal of said circuit changing elements.

4. A device of the character described having a plurality of circuit changing elements, and a plurality of cams adapted to successively actuate said elements, said cams being mounted on a shaft, a step-by-step element associated with said shaft to periodically rotate said shaft, a handle to control said element, and electromagnetic means to control the simultaneous restoration to normal of said circuit changing elements.

5. A device of the character described having a plurality of circuit changing elements, a plurality of cams adapted to successively actuate said elements, said cams being mounted on a shaft, a step-by-step element associated with said shaft to periodically rotate said shaft in a given direction, a second step-by-step element to periodically actuate said shaft in the reverse direction, a handle to control said element, and

electromagnetic means to control the simultaneous restoration to normal of said circuit changing elements.

6. A device of the character described having a plurality of circuit changing elements, a plurality of cams adapted to successively actuate said elements, said cams being mounted on a shaft, a step-by-step element associated with said shaft to periodically rotate said shaft, a handle to control said element, and electromagnetic retaining means for said shaft.

7. A device of the character described having a plurality of circuit changing elements, a plurality of cams adapted to successively actuate said elements, said cams being mounted on a shaft, a step-by-step element associated with said shaft to periodically rotate said shaft in a given direction, a second step-by-step element to periodically actuate said shaft in the reverse direction, a handle to control said element, and electromagnetic retaining means for said shaft.

8. A device of the character described having a plurality of circuit changing elements, and a plurality of cams having angularly disposed actuating means adapted to successively actuate said elements, said cams being mounted on a shaft, a step-by-step element associated with said shaft to periodically rotate said shaft, a handle to control said element, and electromagnetic means to control the simultaneous restoration to normal of said circuit changing elements.

9. A device of the character described having a plurality of circuit changing elements, a plurality of cams having angularly disposed actuating means adapted to successively actuate said elements, said cams being mounted on a shaft, a step-by-step element associated with said shaft to periodically rotate said shaft in a given direction, a second step-by-step element to periodically actuate said shaft in the reverse direction, a handle to control said element, and electromagnetic means to control the simultaneous restoration to normal of said circuit changing elements.

10. A device of the character described having a plurality of circuit changing elements, a plurality of cams having angularly disposed actuating means adapted to successively actuate said elements, said cams being mounted on a shaft, a step-by-step element associated with said shaft to periodically rotate said shaft, a handle to control said element, and electromagnetic retaining means for said shaft.

11. A device of the character described having a plurality of circuit changing elements, a plurality of cams having angularly disposed actuating means adapted to successively actuate said elements, said cams being mounted on a shaft, a step-by-step ele-

- ment associated with said shaft to periodically rotate said shaft in a given direction, a second step-by-step element to periodically actuate said shaft in the reverse direction, 5 a handle to control said element, and electromagnetic retaining means for said shaft.
12. A device of the character described having a plurality of circuit changing elements, and a shaft having means to successively 10 actuate said elements, a step-by-step element with said shaft by which said shaft may be periodically rotated, a second step-by-step element by which said shaft may be periodically actuated in a reverse manner, 15 pawls for said step-by-step elements, means for controlling the association of said pawls with said step-by-step elements, and electromagnetic means to control the simultaneous restoration to normal of said circuit changing elements.
13. A device of the character described having a plurality of circuit changing elements, a shaft having means to successively 20 actuate said elements, a step-by-step element with said shaft by which said shaft may be periodically rotated, a second step-by-step element by which said shaft may be periodically actuated in a reverse manner, 25 pawls for said step-by-step elements, means for controlling the association of said pawls with said step-by-step elements, a handle for actuating said pawls, and electromagnetic means to control the simultaneous restoration to normal of said circuit changing elements.
14. A device of the character described having a plurality of circuit changing elements, a shaft having means to successively 30 actuate said elements, a step-by-step element associated with said shaft by means of which said shaft may be periodically rotated, a pawl for said step-by-step element, 35 a handle for controlling said pawl, and electromagnetic means to control the simultaneous restoration to normal of said circuit changing elements.
15. A device of the character described having a plurality of circuit changing elements, a shaft having means to successively 40 actuate said elements, a step-by-step element associated with said shaft by means of which said shaft may be periodically rotated, a pawl for said step-by-step element, 45 a handle for controlling said pawl, and electromagnetic means to control the simultaneous restoration to normal of said circuit changing elements.
16. A device of the character described having a plurality of circuit changing elements, a shaft having means to successively 50 actuate said elements, a step-by-step element with said shaft by means of which said shaft may be periodically rotated, a pawl for said step-by-step element, 55 a handle for controlling said pawl, and electromagnetic means to control the simultaneous restoration to normal of said circuit changing elements.
17. A device of the character described having a plurality of circuit changing elements, a shaft having means to successively 60 actuate said elements, a step-by-step element associated with said shaft whereby said shaft 65 may be periodically rotated, and electromagnetic means to control the simultaneous restoration to normal of said circuit changing elements.
18. A device of the character described 70 comprising a plurality of independent circuit controlling elements, step-by-step means for successively operating said elements to place them in a given circuit changing position, step-by-step means for 75 successively actuating said elements to restore them to normal condition, a locking device for said means to retain them in their limiting or intermediate positions, and electromagnetic means to control the simultaneous 80 restoration to normal of said circuit changing elements.
19. A device of the character described comprising a plurality of switch elements, step-by-step operating means whereby said 85 switch elements may be successively brought into circuit changing position, a locking device for said means to retain them in their limiting or intermediate positions, and electromagnetic means to control the simultaneous 90 restoration to normal of said switch elements.
- In witness whereof, I hereunto subscribe my name this 9th day of September A. D., 95 1911.

WILLIAM H. GAULKE.
